CLAIM

The ornamental design for a retinopathy instrument tray, as shown and described.

DESCRIPTION

FIG. 1 is a frontal elevation view showing the retinopathy instrument tray;

FIG. 2 is a right side elevation view of the FIG. 1 retinopathy instrument tray, the left side elevation being the same;

FIG. 3 is a lower edge elevation view of the FIG. 1 retinopathy instrument tray, the top edge elevation being the same;

FIG. 4 is a rear elevation view of the FIG. 1 tray;

FIG. 5 is a section view taken on lines 5-5 of FIG. 1;

FIG. 6 is a section view taken on lines 6-6 of FIG. 1;

FIG. 7 is a section view taken on lines 7-7 of FIG. 1;

FIG. 8 is a section view taken on lines 8-8 of FIG. 1;

FIG. 9 is a section view taken on lines 9-9 of FIG. 1;

FIG. 10 is a section view taken on lines 10-10 of FIG. 1; and,

FIG. 11 is a section view taken on lines 11-11 of FIG. 1.

The broken lines are included for the purpose of illustrating portions of the retinopathy instrument tray that form no part of the claimed design.
